UNITED STATES PATENT OFFICE.

DAVID A. PETERS, OF HAGERSTOWN, MARYLAND.

FLEXIBLE FIRE-ESCAPE LADDER.

SPECIFICATION forming part of Letters Patent No. 282,362, dated July 31, 1883.

Application filed April 11, 1883. (No model.)

To all whom it may concern:

Be it known that I, DAVID A. PETERS, a citizen of the United States, residing at Hagerstown, in the county of Washington and State 5 of Maryland, have invented certain new and useful Improvements in Flexible Fire-Escape Ladders, of which the following is a specification, reference being had therein to the accompanying drawings.

10 The object of this invention is to provide an improved flexible ladder which will fold close, thereby adapting it to fire-escape purposes. The apparatus will first be described, and the invention then designated in the claim.

15 In the drawings hereto annexed, Figure 1 is a sectional view of the wall of a building and a window, showing the ladder suspended therefrom. Fig. 2 is a view showing the ladder folded and occupying a recess inside of the 20 building below the window-sill. Fig. 3 is a side view, showing more plainly the ladder and the manner of folding it. Fig. 4 is a top view of a rung detached.

The letter A designates the wall of a building; B, the window; C, an upright cover hinged at the floor, which closes a recess, D, under the window-sill. Suitable eyes or rings, e, are secured in the wall of the inner side below the window-sill. To these the flexible ladder F is secured by any suitable means. In 25 the present instance a bar, g, is secured to the top of the ladder, a straight link, h, is attached by one end to each end of the bar, and the other end of the link is jointed to another link, h', which in turn is jointed to a hook, I, that 30 engages with the eyes e in the wall. By this arrangement of hooks the ladder may be attached to or detached from the eyes at pleasure. The link h', when the ladder is suspended out- 35 side, rests across the window-sill, and when in this position the outer ends of the link project far enough to hold the ladder away from the wall. The distance to which this link should project outside of the wall may of course 40 vary to suit the ideas of the builder.

45 The rungs k of the ladder consist of two flat

bars, 1, of iron, between which a wooden strip, 2, is interposed. The bars and strip, being riveted together, constitute the tread on which the foot is placed. At each end of the rung 50 and between the two bars the ends of three flat bar-links, n n and p, are pivoted by the pin q. The two links n project up, while the link p hangs down; (or, of course, this may be reversed, two down and one up.) The end of 55 each link p of one rung is placed between the ends of the two links n of another rung, and jointed thereto by a pin, r. It will thus be seen the rungs are connected by a two-part jointed link, which parts, when folded by el- 60 bowing outward, as shown in Fig. 3, mesh or fit together close, one part, p, meshing in the other part, n n, so that when folded the two parts together occupy no more space than one alone. By this arrangement the rungs k 65 come together in close contact, and thereby the ladder is folded very closely, enabling a greater length of ladder when folded to be got in less space than heretofore.

If desired, the ladder, instead of occupying 70 a recess below the window, may be stowed away under a bed or other convenient place, as the hooks I provide for its ready attachment to the window in case of fire.

Having described my invention, I claim and 75 desire to secure by Letters Patent of the United States—

A flexible fire-escape ladder consisting of the rungs k, connected by a two-part jointed link, one part being composed of two flat bars, n, 80 and the other part of a single bar, p, placed between them, the said two parts adapted, when folded outward, to mesh together, whereby the rungs may come together in close contact, as set forth.

In testimony whereof I affix my signature in presence of two witnesses.

DAVID A. PETERS.
